CLAIM

The ornamental design for an article of jewelry, as shown and described.

DESCRIPTION

FIG. 1 is a perspective view of a first embodiment of an article of jewelry showing my new design;

FIG. 2 is a side view thereof;

FIG. 3 is a left side view thereof;

FIG. 4 is a right side view thereof;

FIG. 5 is a top view thereof;

FIG. 6 is a bottom side view thereof;

FIG. 7 is a perspective view of the article of jewelry in FIG. 1, shown in an alternate position;

FIG. 8 is a side view;

FIG. 9 is a left side view thereof;

FIG. 10 is a right side view thereof;

FIG. 11 is a top view thereof;

FIG. 12 is a bottom view thereof;

FIG. 13 is a perspective view of the second embodiment of the article of jewelry showing my new design;

FIG. 14 is a side view thereof;

FIG. 15 is a left side view thereof;

FIG. 16 is a right side view thereof;

FIG. 17 is a top view thereof;

FIG. 18 is a bottom side view thereof;

FIG. 19 is a perspective view of the article of jewelry in FIG. 13, shown in an alternate position;

FIG. 20 is a side view thereof;

FIG. 21 is a left side view thereof;

FIG. 22 is a right side view thereof;

FIG. 23 is a top view thereof; and,

FIG. 24 is a bottom view thereof.

The broken lines in the drawings represent portions of the article of jewelry and form no part of the claimed design.
